ATTORNEY

UNITED STATES PATENT OFFICE.

GUSTAVE J. VESTER, OF PROVIDENCE, RHODE ISLAND, ASSIGNOR TO ALFRED VESTER
& SONS, INCORPORATED, OF PROVIDENCE, RHODE ISLAND.

DESIGN FOR A SCONCE FOR A LIGHTING-FIXTURE OR SIMILAR ARTICLE.

55,403.

Specification for Design.

Patented June 1, 1920.

Application filed January 19, 1920. Serial No. 352,633. Term of patent 7 years.

To all whom it may concern:

Be it known that I, GUSTAVE J. VESTER, a citizen of the United States, and a resident of Providence, in the county of Providence and State of Rhode Island, have invented a new, original, and ornamental Design for a Sconce for a Lighting-Fixture or Similar Article, of which the following is a specification, reference being had to the accompanying drawing, forming part thereof.

The figure in the drawing is a view of the

obverse side of the gas and electric light fixture parts or similar articles, showing my design.

I claim

The ornamental design for a sconce for a lighting fixture or similar article, as shown.

GUSTAVE J. VESTER.

Witnesses:

BESSIE P. TOOMEY,
J. A. MILLER.
